Primary Examiner — Alison M Ofstun*Assistant Examiner* — Evin F Ershock(74) *Attorney, Agent, or Firm* — Ryan T. Grace; Advent, LLP**(57) CLAIM**

The ornamental design for a brush, as shown and described.

DESCRIPTION

FIG. 1 is an isometric view of a brush;

FIG. 2 is a top plan view of the brush of FIG. 1;

FIG. 3 is a bottom plan view of the brush of FIG. 1;

FIG. 4 is a front elevation view of the brush of FIG. 1;

FIG. 5 is a rear elevation view of the brush of FIG. 1;

FIG. 6 is a left side elevation view of the brush of FIG. 1; and,

FIG. 7 is a right side elevation view of the brush of FIG. 1. Portions of FIGS. 1 through 7 are shown in evenly spaced broken lines illustrating portions of the article that form no part of the claimed design.

1 Claim, 7 Drawing Sheets(56)
